UNITED STATES PATENT OFFICE.

PAUL RUFFANI, OF DRESDEN, SAXONY, GERMANY.

CARD-HOLDER.

SPECIFICATION forming part of Letters Patent No. 286,382, dated October 9, 1883.

Application filed May 19, 1883. (No model.)

To all whom it may concern:

Be it known that I, PAUL RUFFANI, of the city of Dresden, in the Kingdom of Saxony, and German Empire, have invented certain new and useful Improvements in Card Stands or Holders, of which the following is a specification.

My invention relates to improvements in card stands or holders for holding photographs, cards, price-lists, bills of fare, and other cards in an almost vertical position, as will be seen from the accompanying drawings.

In the said drawings, Figure 1 is a perspective view of my improved stand with an open angular base or foot. Fig. 2 is a perspective view of the same with a base in the form of a cross; and Fig. 3 is a similar view, showing the stand provided with a ring-like circular base. The base or foot may be of any convenient form, the three figures being designed to illustrate as many different shapes.

My said card stand or holder consists of three, four, or more cornered, cross, oval, or annular feet, f, with two bent-up arms. The smaller arm s is formed by cutting or stamping the same out of the broader arm s. The photographs, cards, and such like to be held are inserted between these two arms, and are firmly clasped in the same.

Having now described my said invention for improvements in card stands or holders and the manner in which the same is to or may be carried into effect, I wish it to be understood that what I claim, and desire to secure by Letters Patent, is—

A holder or stand for cards, photographs, and similar articles, consisting of a foot, f, with two bent-up arms, s s', of which the one is formed by being cut or stamped out of the other.

PAUL RUFFANI.
